UNITED STATES PATENT OFFICE.

HERVEY S. WALKER AND HERMON L. VAN VALKENBURG, OF PHILADELPHIA, PENNSYLVANIA, ASSIGNEES TO WALKER ELECTRIC COMPANY, OF PHILADELPHIA, PENNSYLVANIA, A CORPORATION OF PENNSYLVANIA.

PANEL-BOARD.

No. 926,154.

Specification of Letters Patent.

Patented June 29, 1909.

Application filed July 17, 1908. Serial No. 463,959.

To all whom it may concern:

Be it known that we, HERVEY S. WALKER and HERMON L. VAN VALKENBURG, citizens of the United States, residing at Philadelphia, in the county of Philadelphia and State of Pennsylvania, have invented new and useful Improvements in Panel-Boards, of which the following is a specification.

Our invention relates to panel board mounting and construction, particularly as applied to or concerning panel boards used in modern buildings upon the various floors or other places as centers of distribution to a plurality of minor circuits. Such a panel board is ordinarily mounted in a partition wall in vertical position and generally carries a plurality of circuit terminals, switches, bus bars, etc.

It is the object of our invention to provide a panel board mounting or construction whereby the panel board and the linings may be secured vertically or in true alinement with the exterior trim or woodwork surrounding the opening in the partition at the panel board, irrespective of the fact that the means within the partition supporting the panel board may be askew or out of alinement.

It is the further object of our invention to provide a mounting for such purpose which avoids the use of screws or the like entering the panel board or the linings.

Our invention resides in other features hereinafter described and pointed out in the claims, relating particularly to simplicity and cheapness of construction.

For an illustration of one of the forms our invention may take, reference is to be had to the accompanying drawing, in which: 40 Figure 1 is a front elevation of a panel board as mounted within its holder or casing; such casing being shown in section, and one corner of the linings and holder being shown in section as taken on the line X--X 45 of Fig. 2. Fig. 2 is a sectional view through the casing or holder and the woodwork or other trimming and door, the panel board linings and supports being shown in elevation. Fig. 3 is a plan view of a corner angle member. Fig. 4 is a plan view of a

bracket member. Fig. 5 is a perspective view of a lining clamp.

Referring to the drawings, a holder or casing 1, preferably of sheet metal, is formed by plates secured to the angle iron 55 2. Secured by screws or rivets 3 to the bottom or back plate of the holder 1 is a corner angle member 4, shown in plan view in Fig. 3, preferably of cast metal, and provided at its corner with a hole 5 to receive the lag screw or bolt 6 which passes through the member 4 and the back or bottom plate of the holder 1 to secure such holder and attached parts to the frame or other parts of the building, such holder 1 being preferably located within a partition wall. There is such a member 4 and screw or bolt 6 at each of the four corners, two only being shown in Fig. 1.

In each leg of the member 4 is a slot 7 terminating in the enlargement 8 to receive a head of a bolt or screw 10, such head being adapted to slide longitudinally on the leg in the cut out portion 9, while the shank of the screw or bolt moves in the narrower slot 7.

The bolts or screws 10 pass upwardly through the slots 7, their preferably squared heads 11 engaging in the grooves or channels 9 to prevent rotation of the screw shanks 80 10. These screws or bolts 10 extend also upward through the slots 12 in the legs of the bracket member 13, shown in plan view in Fig. 4, the wing nuts 14 engaging the screws 10 and serving to tighten them and clamp the legs 85 of the bracket member 13 to the legs of the angle member 4. Integral with and extending vertically from the bracket member 13 are the cheeks 15 tied together by the ties 16 and 17. The cheeks 15 have their faces at 90 right angles to each other, each cheek face being disposed at right angles to the leg of the bracket member with which it is integral, the legs of the bracket member being joined by the corner plate or segment 18 which is 95 flat faced parallel to the bottom or back of the holder or casing 1. Between the cheeks 15 is an opening below the tie 17.

The panel board 19, of slate or other suitable insulating material, and carrying the 100

bus bars 20, switches 21, fuses 22, and circuit terminals 23, is rectangular in shape and rests, with its corners, upon the corner segments 18 of the bracket members 13, the 5 corners of the panel board 19 passing between the cheeks 15, as indicated by the dotted line 24, in Fig. 4.

Passing through the tie 16 of each bracket member 13 is a screw or bolt 25 having for 10 the head the member 26 having faces disposed at right angles to each other and adapted to engage the inside faces of the linings 27 which may be formed of slate or other suitable insulating material, disposed at right 15 angles to the panel board 19. A wing nut 28 on the outside of the tie 16 serves to draw the member 26 firmly against the insides of the linings 27 and hold them firmly against the cheeks 15 and thus firmly in position, 20 the linings 27 and the panel board 19 forming a shallow open box of insulating material.

Passing under the wing nut 28, and clamped between it and the tie 16, is a further clamp 29, as shown in Fig. 5, slotted 25 at 30 to be adjustable with respect to the screw 25. The clamp 29 terminates in a head 31 at right angles to the portion 29 and engages the top corners of the linings 27. 30 The linings 27 do not come together at their corners but leave a gap through which the screw 25 passes. Between the linings 27 and the inside of the casing or holder 1 is left a trough in which are laid the electrical conductors leading to the bus bars 20 and the circuit terminals 23, such conductors passing out to the different circuits in the building through any suitable opening.

During the construction of a building, the 40 holder or casing 1, with the attached angle members 4, is built in or secured in position in a partition wall, the top or front edge of the holder being placed to come approximately flush with the wall. Upon the completion of the building, the wooden trim or 45 molding 32 is placed as an ornamental finish to cover the holder or casing, an opening for the door 33 being provided, such door having a glass panel 34, if desired, the door opening 50 being substantially the same size and shape as the panel board. Later, or before the trim 32 is put in place, the brackets 13 are placed and then the panel board 19 and the linings 27, the brackets 13 being slid or adjusted with respect to the angle members 4 55 and then tightened when the panel board is in alinement with the trim, irrespective of whether the holder 1 is askew or in alinement. And the linings 27 are clamped by 60 the means described, that is, both by the member 26 and the clamp 29.

From the foregoing description, it is apparent that the panel board and linings need not be drilled for the reception of screws or 65 other fastening means, but that they may be

adjustably secured in position by clamping screws or bolts carried by members which are suitably adjustable to compensate for any lack of alinement between the casing or holder and the outside finish upon the wall. 70

The parts being, preferably, of sheet metal, such as sheet iron, and of castings, as cast iron or malleable castings, and there being no drilling or accurate fitting of the parts required, affords a cheap and yet 75 highly efficient structure and mounting for panel boards.

What we claim is:

1. The combination with a plate, of angle members secured thereto, bracket members, 80 means for adjustably clamping said bracket members to said angle members, a panel board, said bracket members having sockets to receive said panel boards, linings, and means for clamping said linings to said 85 bracket members.

2. In a panel board mounting, the combination with a plate, of slotted angle members secured thereto, slotted brackets, means for adjustably securing said brackets to said 90 angle members, a panel board, said bracket members having openings to receive said panel board, linings, and means for clamping said linings to said bracket members.

3. In a panel board support, an angle 95 member having legs disposed substantially at right angles to each other and in the same plane, said legs having slots to receive adjustable securing means, a panel board, and a support therefor attached to said angle 100 member.

4. In a panel board support, a bracket member comprising slotted legs disposed at right angles to each other, cheek members on said bracket member, there being a gap 105 between said cheek members to receive a panel board, and a tie between said cheek members.

5. In a panel board mounting, the combination with an adjustable bracket member, 110 of a supporting member means for securing bracket member to said supporting member, and a lining clamp on said bracket member, said bracket member having an opening to receive and support a panel 115 board.

6. In a panel board mounting, the combination with an angle member, of a bracket member, said angle and bracket members each having slotted legs disposed at an angle 120 to each other, means for adjustably securing said bracket member to said angle member, and a panel board supported by said bracket member.

7. In a panel board mounting, a bracket 125 member having an opening to receive and support a panel board, and a clamp on said bracket member for clamping a lining thereto.

8. In a panel board mounting, a bracket 130

member comprising cheek members, a tie and a corner plate joining said cheek members, said bracket member having an opening formed between said tie and corner plate 5 to receive a panel board.

9. In a panel board mounting, a bracket member having cheek members disposed in planes at right angles to each other, a clamp carried by said bracket member between 10 said cheek members for clamping linings against said cheek members, a member of said clamp extending between said linings.

10. The combination with a sheet metal casing, of angle members secured thereto, 15 bracket members adjustably secured to said angle members, said bracket members having openings to receive and support a panel board, and lining clamps on said bracket members.

20 11. In a panel board mounting, the com-

bination with angle members, of bracket members adjustably secured thereto, said bracket members having openings to receive a panel board, and lining clamps on said bracket members. 25

12. In a panel board mounting, a bracket member, a lining, a clamp on said bracket member for engaging a side of said lining, and a second clamp on said bracket member engaging an edge of said lining. 30

In testimony whereof we have hereunto affixed our signatures this 16th day of July, 1908, in the presence of the two subscribing witnesses.

HERVEY S. WALKER.

HERMON L. VAN VALKENBURG.
